UNITED STATES PATENT OFFICE.

EDWARD A. LANGENBACH, OF CANTON, OHIO.

DESIGN FOR A METALLIC CEILING-PLATE.

SPECIFICATION forming part of Design No. 26,446, dated December 22, 1896.

Application filed November 9, 1896. Serial No. 611,571. Term of patent 7 years.

To all whom it may concern:

Be it known that I, EDWARD A. LANGENBACH, a citizen of the United States, and a resident of Canton, county of Stark, State of Ohio, have invented a new and useful Improvement in a Design for Metallic Ceiling-Plates, of which the following is a full, clear, and exact description, reference being had to the accompanying drawings, making part of this specification.

My invention relates to a new design for metallic ceilings; and it consists of a ceiling of the configuration and ornamentation shown in the accompanying drawings, in which—
Figure 1 is a view in elevation of my new ceiling-plate. Fig. 2 is a sectional view on line $y-y$, Fig. 1; and Fig. 3 is a similar view on line $z-z$, Fig. 1.

The leading features of my design consist of the sides A, corners B, and body portion C of the configuration and ornamentation shown, which I will now proceed to describe in detail.

Each side piece A consists of a rectangular strip having a roll 1, the edge of which is provided with a row of ornamented beads 2, and the inner corners of each side section has ornamented quadrantal figure 3, forming substantially a triangular field 4, ornamented with a three-pointed figure 5, formed of scrolls and straight and curved lines. The corner

sections are square in outline and are each of the same configuration and ornamentation as the side sections, with the exception that each corner section has but one ornamented quadrantal figure, thus forming with the angular roll 6 a right-angular field 7, ornamented by a figure 8, composed of scrolls and straight and curved lines.

The center or body portion C of the ceiling is square in outline and has at its four corners quadrantal figures 9, identical with those above described and matching the same. The central field formed by these four figures is ornamented by a four-pointed figure 10, formed of scrolls and straight lines, from the center of which projects a circular bead 11.

A metallic ceiling of the configuration and ornamentation shown in the accompanying drawings is very pleasing to the eye and materially adds to the appearance of the room where used.

What I claim is—

The design for a metallic ceiling as herein shown and described.

In testimony whereof I have hereunto set my hand this 28th day of October, A. D. 1896.

EDWARD A. LANGENBACH.
